Fross, Zelnick, Lehrman & Zissu, P.C.(57) CLAIM

The ornamental design for a bottle, as shown and described.

DESCRIPTION

FIG. 1 is a perspective view of the bottle showing my design with the cover;

FIG. 2 is a top view thereof;

FIG. 3 is a front view thereof (the back view being a mirror image);

FIG. 4 is a side view thereof (the other side being a mirror image);

FIG. 5 is a perspective view shown with the cover removed for a clear disclosure of the underlying portion;

FIG. 6 is a top view thereof;

FIG. 7 is a front view thereof (the back view being a mirror image); and,

FIG. 8 is a side view thereof (the other side being a mirror image).
